COLOSTOMY CUP

Murle Perry, Minneapolis, Minn.

Application March 20, 1939, Serial No. 263,031

1 Claim. (Cl. 128—283)

The invention relates to a surgical appliance and more especially to a colostomy cup.

The primary object of the invention is the provision of a cup of this character, wherein the same is readily applicable for service in certain abdominal operations so that there will be no discomfort to a person operated upon and sediment flowing from the incision will be caught within the cup, the latter being readily removable from the person wearing the same and while being worn eliminates the escape of bad odors from the flow into the said cup, the removability of the latter permits of easy cleaning and the emptying of its contents so that it will be thoroughly sanitary.

Another object of the invention is the provision of a cup of this character, wherein the same carries a dispensable inner liner or bag for receiving sediment or matter running from an incision so that the cup will be more sanitary and enabling the emptying and cleaning thereof with dispatch and ease.

A further object of the invention is the provision of a cup of this character, wherein the same is made from metal having a removable lid and thus convenient access is had to the interior thereof and maximum life is assured, the body of the cup being of a construction to assure comfort to a wearer, avoiding soreness and leakage when in wearing position, the cup being supported by a belt to be fastened about a person and such cup can be readily removed without removal of the belt and such removal had with dispatch, the inlet side of the cup being of a character to effect a broad seating surface and when applied to the body of a person assures a support to the tender tissues around the incision or colostomy, being a pad interposed between the inlet side of the cup and the body of the person to avoid contact of such cup with the skin resulting in perfect comfort and increasing sanitation during the use of such cup.

A still further object of the invention is the provision of a cup of this character, wherein there is produced a sediment bowl carried considerably beneath the entrance to said cup so that matter flowing into the cup drops down away from the colostomy and in this way avoids infection and leakage of such matter from the cup.

A still further object of the invention is the provision of a cup of this character, wherein the same houses a dispensable inner lining or bag which receives matter delivered from an incision into the cup, this lining or bag being readily removable for the throwing away of the same and

in this manner keeping the cup cleaned within to avoid staining thereof, and receptive of a fresh or new liner or bag, the cup construction being such that it can be sterilized and rendered sanitary.

A still further object of the invention is the provision of a cup of this character, which is simple in its construction, thoroughly reliable and efficient in operation, readily and easily applied and removed, and inexpensive to manufacture.

With these and other objects in view, the invention consists in the features of construction, combination and arrangement of parts as will be hereinafter more fully described, illustrated in the accompanying drawing, which discloses the preferred embodiment of the invention and pointed out in the claim hereunto appended.

In the accompanying drawing:

Figure 1 is an elevation of the cup constructed in accordance with the invention looking toward the mouth or entrance side thereof.

Figure 2 is a view similar to Figure 1 looking toward the opposite side.

Figure 3 is an enlarged sectional view taken on the line 3—3 of Figure 2 looking in the direction of the arrows and in an applied position.

Figure 4 is a perspective view of the inner liner or bag for the cup.

Similar reference characters indicate corresponding parts throughout the several views in the drawing.

Referring to the drawing in detail, A designates generally the cup constituting the present invention and generally worn on a belt, a portion of the belt being indicated at B, which at one end carries a buckle 10 for adjustable connection of the other end of said belt therewith so that the belt can be worn about the body of a person for sustaining the cup in an applied position for the catching of flowing matter from an incision made in a surgical operation upon the person.

The cup A comprises a bowl-like body 10 more especially of saucer shape having opposite a concavo convexed permanently closed side 11 a flattened open side 12, the opening being circular and marginally outwardly flanged at 13. The opening in the side 12 is eccentrically disposed and removably fitted upon its flange 13 is a mouth lid 14 having a circular entrance mouth 15, being centered in the said lid 14. The lid 14 concentric to the mouth 15 is slightly concaved at 16 and this mouth has an inwardly protruding annular lip 17 extending inwardly of the body 10 when the lid 14 is placed over the opening and frictionally telescoped upon the flange 13 thereof.

- Adapted to be inserted into the body 10 when the lid 14 is removed through the opening confronted by such lid is a dispensable inner liner or bag 18, preferably made from waterproof paper so that matter flowing from an incision through the mouth 15 will be collected in the said liner or bag 18 when within the body 10 and this bag when containing such matter may be readily thrown away on removal from the cup.
- 10 The lid 14 has an annular rim 19, the free edge thereof being serviceable as a cutter for severing the liner or bag 18 when overriding the flange 13 of the opening in the flat side 12 of the body 10 of the cup and in this way relieving any surplus extent of the liner or bag when carried within the body 10 for the packing of secretion or matter flowing from an incision in the use of the cup in colostomy surgical operations.
- 15 The side 11 of the body 10 has permanently carried thereby spaced pairs of oppositely arranged hooking clips 20, their bills 21 being directed toward each other in the respective pairs and in this manner the belt can be removably engaged and hooked by the clips for the mounting of the cup in wearing position thereon, the cup being readily removable from the belt B when fastened about the body of a person without removal of the belt. The clips 20 are arranged on the body 10 so that the opening for the lid 14 will be uppermost of the body 10 and in this fashion when the cup is worn the body will assume a drop bowl position so that matter flowing into the body will settle in the portion of the body lowermost to the opening for the lid 14 without possibility of leakage through the mouth 15 when the lid 14 is applied to said body.
- 20 To avoid discomfort to a person wearing the cup and eliminate contact of the lid 14 with the body of such person or the contact of the flat side of said cup with the body, there is interposed between this flat side 12 and the body of the wearer a suitable protective pad, preferably made from a thin cellucotton pad 22 having the hole 23 cut therein in register with the mouth 15 of the lid 14 and by reason of the formation of the lid 14 in the flat side 12 of the body 10 a broad seating surface of the cup with the pad is assured, being no possibility of the mouth 15 or the lid coming in contact with the body of the wearer of the cup during the use of the latter and also this pad 22 in applied relation with the cup to the person eliminates the escape of bad odors from the said cup through the open mouth 15. The pad carried a suitable waterproof backing, denoted at 24, being discovered that the backing can be made from crepe waterproof paper and such backing in the wearing of the pad is disposed between the cup and the body, being next to the person's body. The creped backing to the pad prevents moisture that may

sometimes seep down from the colostomy from soaking clean through the pad to the body while the cellucotton constituting the pad body absorbs the moisture and the latter does not penetrate through the backing. Thus in the use of the pad, the body is always dry and comfortable and there is no liability of the slipping or shifting of the pad with relation to the body. Perfect comfort is assured to the patient or person while wearing the cup and the removal of such cup with dispatch is had and such cup can be readily cleaned for sanitary purposes in that it can be sterilized without affecting wearing qualities, the sacked matter being readily thrown away in that the liner or bag 18 can be taken out of the cup or body 10, being made from paper can be conveniently destroyed. It is preferable that the body 10 and the lid 14 be made from metal although it may be made from other suitable material withstanding requirements in the use of the cup for the cleaning thereof and durability, as, for example, made from glass, Bakelite or the like, while the liner or bag 18 is preferably made from waterproof flexible fibrous material, such as paper. The liner or bag when inserted in the body 10 through finger manipulation can be shaped for fitting therein, that is to say, when such liner or bag is dry, and the latter when becoming moist will shape itself to the interior of the cup.

In the wearing of the cup in association with the pad, the lid 14 and the flange 13 of the opening become counterseated or countersunk in the said pad, as is clearly shown in Figure 3 of the drawing, the cup and pad being in wearing position in this view in the said drawing.

What is claimed is:

A colostomy apparatus comprising a cup having a closed outer wall, an inner wall for said cup having an opening therein said opening being formed with an outwardly projecting neck, a dispensable bag in said cup, the mouth of said bag being placed so as to project through the neck of the cup, an annular cover member for said opening, said cover member being formed with inner and outer circumferential flanges projecting in the same direction, the outer flange being adapted to grip the outer surface of the outwardly projecting neck of the inner wall with the mouth of the dispensable bag adapted to be gripped therebetween, and the inner circumferential flange being smoothly curved inwardly with respect to said cup, a cellulosic pad of absorbent material having an aperture smaller than the opening in the annular member adapted to be disposed with said aperture in registry with said opening and between the annular member and the body of the wearer, and means adapted to hold said assembly on the body of the wearer.
